MARKING ROLL

Application filed April 17, 1930. Serial No. 445,180.

This invention relates to a marking roll and more particularly, to such a device to be used in conjunction with a paper making machine in order to impress a design on the paper as it moves therethrough.

Rolls of this type are generally located in the paper machine adjacent the press or drying rolls with which they cooperate in marking the paper web as it passes thereover.

In practice these marking rolls assume various constructions and often comprise a metal roll having metal marking plates or types secured thereto, the marking plates being covered with a fabric wrapping to prevent the same from cutting the paper.

Other designs of such rolls include metal rolls having rubber marking surfaces either secured directly thereto or to endless bands of soft rubber which are in turn made fast to said metal rolls.

Many commercial disadvantages arise from the use of these forms of rolls, particularly with relation to the life of the rolls, the difficulty of changing or renewing the design of the rolls and of assembling and dismantling the rolls on their supporting shaft and the original and replacement cost of the rolls. For instance, with regard to the first mentioned type of marking roll, it is necessary to wrap the marking surfaces of the same with fabric which wears easily and, as a result, must be frequently replaced. This operation requires considerable time and also involves a serious expense.

On the other hand, with rolls having rubber marking surfaces the changing or renewing of the marking surfaces and the assembly of the rolls is a tedious operation and also an expensive one.

We have now devised a marking roll which is singularly free from the objectionable features of known rolls in that it can be quickly and easily assembled, permits the renewal of its marking design by a simple, inexpensive operation, is not restrictively expensive and has a high utility in forming impressions on paper, especially, in paper making machines.

These results are accomplished by forming a marking roll with a marking sleeve made

up of a plurality of alternate layers of hard rubber and fabric, the outer surface of the sleeve being of hard rubber having a design incorporated or engraved therein. The various layers are removably secured together so that it is possible to strip the layers from one another to expose the successive hard rubber surfaces which can then be engraved to form new marking surfaces. The marking sleeve is made with a bore of larger diameter than its supporting roll or shaft which provides for a ready removal of the sleeve from and a positioning of the sleeve on the supporting roll.

It is, accordingly, an object of this invention to provide a marking sleeve which can be quickly and easily mounted on and removed from a supporting roll shaft.

It is a further object of this invention to provide a marking roll comprising a marking sleeve and supporting roll or shaft therefor having a much smaller diameter than the diameter of the bore of the marking sleeve.

It is a further object of this invention to provide a marking roll wherein the design of the roll can be renewed or replaced by a simple, inexpensive operation.

It is a further object of this invention to provide a marking sleeve having a plurality of layers of hard engraving rubber separated by layers of heavy fabric, the various layers being removable to expose the successive hard rubber layers.

Other and further important objects of this invention will become apparent from the following description and appended claims.

Referring now to the drawings which disclose a preferred embodiment of our invention.

Figure 1 is a fragmentary longitudinal sectional view through the marking sleeve of this invention.

Figure 2 is a cross section of the sleeve of Figure 1.

Figure 3 is a view similar to Figure 1 showing the sleeve after the outer engraved layer and its fabric backing have been removed to expose the second layer of hard rubber which is shown as engraved.

Figure 4 is a front elevation of the marking sleeve mounted on its supporting roll, with parts shown in section.

On the drawings:

- 5 The marking sleeve of this invention comprises a hollow cylindrical body 1 formed of a plurality of alternate layers of rubber and heavy fabric secured together. The innermost or supporting layer 2 is composed of medium, hard, tough rubber. This layer is surrounded by several thicknesses of heavy fabric or duck 3, the outer surface of which is provided with a friction coating as at 4. A layer 5 of hard rubber or engraving gum of suitable thickness is vulcanized to the friction coated fabric 3. Over this layer of rubber or gum is a second layer 6 of friction coated fabric to which is vulcanized a final layer 7 of hard rubber or engraving gum forming the exterior surface of the sleeve.
- 10 The ends of all but the inner layer 2 are cut away as at 8 for the reception of hard rubber caps 9 which protect the fabric layers from the action of steam and heat when the sleeve is mounted for operation in the paper machine. These caps are made of such width as not to interfere with the design on the marking surface of the sleeve or the deckle size of the paper sheets.
- 15 25 30 A sleeve constructed as above when desired to be employed in a marking roll is engraved with a design 10 by mounting the sleeve on a support and cutting away portions of the outer hard rubber layer 7 to form said design. In engraving this layer, the design is cut therein the full depth of the layer as shown in Figure 3 and the parts so cut out are pulled away or stripped from the fabric backing layer 6. In order to readily permit this stripping action without tearing the rubber layer, the vulcanization of said layer to its fabric backing is only carried out to such an extent as to produce a firm adhesion between the two layers.
- 35 40 45 The engraved marking sleeve is mounted in the paper machine on a supporting press roll 11 (Figure 4) of smaller diameter than the bore of the sleeve, so that a clearance 12 exists between the press roll and sleeve. The supporting press roll 11 is located in the paper machine in a position to cooperate with the drying cylinder or a press or similar roll so as to be moved thereby in marking the paper web. Preferably a guide bar carrying a plurality of guides is located on the supports for the roll 11 whereby to position a number of marking sleeves on the width of said supporting press roll.

50 55 60 The operation of the marking sleeve, as stated above, is effected by positioning the sleeve and its supporting roll adjacent to a roll over which the paper to be marked moves, preferably, a drying cylinder or press roll. The friction set up between the marking sleeve and the cooperating roll causes the

supporting press roll and sleeve to rotate as a unit similar to the movement of a loose belt of large diameter over a rotating pulley of less diameter. The web of paper coming in contact with the rotating sleeve is impressed 70 with the design carried thereby.

In practice it will be found that the weight of the press roll supported at its ends will cause a slight "springing" of the roll so that the marking sleeve on the roll will be slightly 75 depressed near its center, thus producing a non-uniform mark on the paper web. This defect can be overcome by crowning the supporting press roll, whereupon the marking sleeve will conform to the contour of said 80 roll.

It will be apparent that the frictional contact between the surface of the marking sleeve and the roll with which it cooperates will after a certain time cause a wearing 85 away of the design on the marking sleeve. When wear of the design has progressed to such an extent that the mark on the paper web no longer assumes a clear cut impression, it is necessary to renew the design on 90 said sleeve. In the rolls formerly employed this meant either the replacement of the marking roll by another roll, the stripping 95 of the marking surface of the roll from the roll proper, or the re-engraving of the surface of the worn roll, which acts entailed a tedious, expensive operation. The marking face of our roll on the other hand, is renewed by a comparatively simple procedure.

The marking sleeve is slid off its supporting press roll and mounted on a mandrel or similar support. The engraved rubber surface 7 and its layer of fabric backing or duck 6 is then stripped from the roll, thereby exposing the hard rubber layer 5. The outer 105 surface of this layer is then worked to clean and smooth the same and the rubber cap 9 worked down to proper size or replaced by caps of proper height. The desired design 10a is then engraved in the layer 5, whereupon 110 a sleeve as shown in Figure 3 results.

By forming the marking sleeve with a bore diameter greater than that of the supporting press roll it is apparent that a number of various modifications of the mounting of the sleeve in the machine may be employed. For instance, a series of sleeves of different design may be located on a supporting roll in position to mark different widths of paper so that various combinations of paper to suit manufacturing requirements can be made from the same grade of paper. Furthermore, a series of supporting rolls of various lengths may be mounted within the width of the machine and the marking sleeves on these rolls impressed 115 against the paper as required.

It should also be borne in mind that while we have disclosed a marking sleeve having two layers of engraving gum thereon, this is not a limitation as any number of such layers 130

may be used consistent with commercial feasibility of manufacture and operation.

It will be appreciated from our disclosure that we have constructed a marking sleeve of high efficiency in that it permits the renewal or replacement of its marking surface by a simple operation; can be easily and quickly mounted in and dismounted from a supporting roll and can be arranged in various ways in the machine to effect different markings on the paper web.

While we have disclosed a preferred embodiment of our invention, it is to be understood that various changes in the structure thereof may be made without departing from the spirit of the invention disclosed. Accordingly, we do not propose to limit our invention except as necessitated by the prior art.

We claim as our invention:

1. A marking sleeve, comprising a hollow body having an outer layer of hard rubber with a design therein, a backing of heavy fabric therefor, and a second layer of hard rubber removably secured to said fabric backing whereby said engraved rubber layer and its fabric backing may be stripped from the sleeve to expose said second rubber layer.

2. A marking sleeve, comprising a hollow cylindrical body having a design thereon and composed of a plurality of laminated layers of hard engraving gum and heavy fabric removably secured together whereby said laminated layers may be stripped from each other to expose the successive engraving gum surfaces, when the design in the outer of said surfaces wears out.

3. A marking roll, comprising a supporting roll and a hollow marking sleeve loosely and freely mounted thereon, said sleeve including an outer engraved layer of hard rubber, a backing of heavy duck and a second layer of hard rubber adapted to be exposed by removal of said first hard rubber layer and heavy duck when the engraving of said first rubber layer wears out.

4. A marking sleeve, comprising a cylindrical body composed of alternate layers of hard rubber and heavy duck removably secured together.

5. A marking sleeve, comprising an inner supporting layer of medium hard rubber, a layer of heavy fabric thereon, a layer of engraving gum on said fabric layer, a second layer of heavy fabric over said gum, and an outer layer of engraving gum having a design thereon, said outer layers of gum and fabric being removable upon wear of said design, to expose the inner layer of engraving gum.

6. A sleeve as in claim 5 having cylindrical hard rubber caps on the ends thereof.

7. In a paper machine, a marking device for a paper web, comprising a supporting roll, a marking sleeve loosely and freely

mounted thereon and comprising a plurality of superimposed layers of engraving gum each having a backing of heavy duck, the outer layer of gum having a design thereon, and means for frictionally engaging said sleeve for rotating said sleeve and roll as a unit into contact with said paper web.

8. A marking roll comprising a cylindrical support having thereon a laminated marking sleeve of a slightly larger bore diameter than the diameter of said supporting roll, the laminations of said sleeve being such that the outer layer may be stripped from the sleeve to expose a different marking surface.

In testimony whereof, we have hereunto subscribed our names at Port Edwards, Wood County, Wisconsin.
